J. F. GEISENDORFER.

COOKER.

APPLICATION FILED OCT. 13, 1919.

1,419,670.

Patented June 13, 1922.

UNITED STATES PATENT OFFICE.

JOHN F. GEISENDORFER, OF SACRAMENTO, CALIFORNIA.

COOKER.

1,419,670.

Specification of Letters Patent. Patented June 13, 1922.

Application filed October 13, 1919. Serial No. 330,339.

To all whom it may concern:

Be it known that I, JOHN F. GEISENDORFER, a citizen of the United States, residing at Sacramento, in the county of Sacramento, and State of California, have invented a new and useful Improvement in Cookers, of which the following is a specification.

This invention relates to a cooker, and especially to a portable steam actuated cooker for use on automobiles and like vehicles.

One of the objects of the present invention is to provide a simple, compact, durable cooker adapted to be conveniently carried on an automobile and whereby the meals or food required during an automobile journey may be cooked or kept warm while traveling. Another object of the invention is to provide means actuated by the exhaust heat of the engine for generating a sufficient volume of steam to operate the cooker while traveling. Further objects will hereinafter appear.

25 Referring to the accompanying drawings—

Fig. 1 is a side elevation of an automobile showing the application of the invention.

Fig. 2 is a central, vertical, longitudinal section of the cooker.

Fig. 3 is a detail sectional view of the exhaust manifold, showing the steam generating portion of the apparatus.

Fig. 4 is a detail view, partly in section, of a sight feed, whereby the water delivered to the steam generator is regulated.

Referring to the drawings in detail, 40 A indicates in general an automobile, 2 the running-board and 3 the cooker. The cooker is in this instance suitably secured on the running-board and it is supplied with steam by means of a pipe 4, which is connected with a generator generally indicated at 5. The generator proper is placed within the 45 exhaust manifold 6 of the engine and it consists of a vertically positioned U-shaped tube or coil 7, to which water is admitted by means of a pipe 8. This pipe is connected with a sight feeder, generally indicated 50 at 9, which in turn is supplied with water by means of a pump 10, connected with a supply tank 11.

The pipe 8 is connected with the lower portion of the sight feed, as shown at 12, 55 while the supply pipe 13 conveying the water from the pump is connected with the

upper portion of the sight feed, as at 14. Formed in this upper portion of the sight feed is a pocket 15 from which any excess of water supply overflows into a second 60 pocket 16, said pocket being connected by means of a pipe 17 with the return side of the pump or the supply pipe 18, whereby water is conveyed from the tank 11 to the pump.

65 Forming a communication between the pocket 15 and the lower portion of the sight feed or the pipe 12 is a communicating passage 19, through which the quantity of water delivered is regulated by means of a needle 70 valve or adjusting screw 20. The water escaping through the passage 19 and entering the lower portion of the sight feed drains through the pipe 8 and enters the lower portion of the U-shaped coil 7. It is here 75 partially turned into steam and is entirely evaporated before it escapes through the upper coil and the pipe 4; that is the coil of the generator is placed directly in the path of the escaping or discharging exhaust 80 gases and is thus subjected to a temperature which is more than sufficient to generate the volume of steam required.

The pipe 4 enters the side of the cooker, as shown at 4^a, and any condensation or excess steam supplied is permitted to escape through a drain connection 22, formed in the bottom of the cooker.

The cooker proper may be constructed in any suitable manner but preferably as here 90 shown. That is, an interior chamber 23 is provided for the reception of cooking utensils, such as shown at 24 and 25. The walls of the chamber 23 and the cover for the top of the cooker are preferably heat-insulated with asbestos or similar material, as shown at 26. The heat of the steam admitted is thus conserved as a comparatively small quantity is conducted through the walls of the cooker proper.

100 Placed in the bottom of the cooker is a grid or stand 27, which is provided for the reception of the cooking utensils. This permits a free circulation of steam over, under and around the utensils, thus permitting a 105 free circulation and even exposure to the steam. A rigid casing and adjustments, such as safety valves, pressure gages and the like, are not required in the present instance and the operation of the cooker may 110 be performed with absolutely safety as pressure is not employed; that is, the steam ad-

mitted through the opening 4^a is permitted to freely circulate between the cooking utensils and is then permitted to freely escape through the vent or overflow connection 22.

5 The quantity of steam admitted to the cooker determines to a great extent the temperature within the cooker and the time required for cooking the products placed 10 therein, and as the quantity of steam generated depends entirely upon the quantity of water supplied to the generator, it can readily be seen that the screw 20 may be regulated so that the cooking may be timed so 15 that a meal may be completed in a hurry, if desired, or prolonged as occasion may demand.

From the foregoing description it can be seen that I have provided a cooker whereby 20 the food required on an automobile journey may be cooked or kept warm while traveling, thus permitting the serving of hot meals and drinks whenever desired, and that this convenience is obtained without 25 additional consumption of oil or in any way detracting from the usual power and functioning of the engine.

While a more or less specific construction and arrangement is shown throughout, I 30 wish it understood that various changes in the design and proportions of the device may be resorted to within the scope of the appended claims and also that the materials and finish of the several parts employed 35 may be such as the experience and judgment of the manufacturer may dictate.

Having thus described my invention, what I claim and desire to secure by Letters Patent is—

40 1. A cooking attachment for an automobile consisting of a housing having a chamber formed therein for the reception of cooking utensils, an inlet pipe connected with said chamber, a steam generator located in the exhaust manifold on the engine 45 with which the inlet pipe is connected, a water supply tank, a pump by which water is delivered to a needle valve, a pipe connect-

ing said needle valve with the generator, said needle valve adapted to regulate the 50 flow of water to the generator and a by-pass pipe from the needle valve by which surplus water is returned to the tank.

2. The combination with the engine of an automobile, of a steam generating pipe 55 placed within the exhaust manifold, a sight feed, a water supply tank and a pump for delivering water from the supply tank to the sight feed, a needle valve in the sight feed for regulating the quantity of water 60 passing through the sight feed, a pipe connecting the sight feed with the steam generating pipe and delivering a regulated quantity of water thereto, a cooker on the automobile having a chamber therein for the 65 reception of cooking utensils, a pipe connected with the steam generating pipe and conveying steam to the cooking chamber, and a discharge connection in the bottom of the cooker to prevent collection of condensed 70 water and also to prevent formation of steam under pressure.

3. In an automobile cooking attachment of the character described a steam generator positioned in the exhaust manifold of 75 the engine, a water supply tank and a pump, a pipe leading from the pump to a valve, a by-pass pipe from which surplus water may be returned from the valve to the tank, a second pipe connected with the 80 generator, the flow of water through said pipe being regulated by the valve, a non-conducting jacketed casing having a cooking chamber formed therein for the reception of cooking utensils, a vent pipe in the 85 bottom of said casing and communicating with the cooking chamber, and a pipe connecting the steam generator with the cooking chamber.

In testimony whereof I have hereunto set 90 my hand in the presence of two subscribing witnesses.

JOHN F. GEISENDORFER.
